UNITED STATES PATENT OFFICE

LUCIAN F. EASTON, OF LA CROSSE, WISCONSIN

VACUUM HEATING SYSTEM

Application filed June 15, 1929. Serial No. 371,200.

This invention has particular reference to vacuum heating systems.

An object of the invention is to provide a pumping system whereby, without interrupting the movement of the pump or pumps used in the system, substantially the entire pumping load may be eliminated from the driving mechanism for the pump or pumps.

Another object of the invention is to provide a pumping system that employs pumps for removing both air, vapors or gas, and liquids, respectively, from a source of supply, and so govern the operation of the respective pumps that each of the pumps is in effective operation while the other pump ceases to function; and also to so arrange and control the respective pumps that each is successively operative to pump and non-operative for pumping purposes for a period, the active condition of each pump being timed to be simultaneous with the non-operative period of the other pump.

Another object of the invention is to so control the active and non-active periods of the respective pumps that they will be selectively governed by the status in the system of the substances being pumped, so that each substance to be pumped is in fact pumped only when the necessity for such pumping occurs, whether the necessity for such pumping occurs at regular or irregular intervals, and to so arrange the various parts for the purposes of the invention that the control thereof shall be accurate and positive.

Another object of my invention is to increase the efficiency of the pumps by keeping the vacuum pump cool and the head against which the water pump works at a minimum.

The invention may be applied with great advantage to an ordinary vacuum steam heating system, of which it becomes a part, in which an air pump is used to withdraw air, gas and vapors from the coils and pipes and discharge them into the air or other desirable place, so that the live steam or vapor from the boiler may be carried freely to the radiators, the vacuum pressure created by the air pump thereby permitting the evolution of steam at a much reduced pressure; and a

water pump is used to withdraw the water of condensation from the return pipe and pass it again to the boiler; but the invention is also adapted to a large range of uses for other purposes.

In pumping systems heretofore in use, there has been no way, so far as I am aware, in which each of two pumps, used conjointly with each other, and operated by a single power mechanism, could be alternately operated to do its work and at the same time cause the other pump to cease its function and relieve the pumping power mechanism entirely of its pumping load during its temporary idle time. Moreover, most of the loads of both pumps have been constantly put upon the power with a constant use of power for the aggregate load; and no apparatus has been provided whereby the conditions of the fluids within the system itself would selectively determine when one pump or the other should function to pump its peculiar content of the system.

In a vacuum steam heating system, for instance, the water of condensation and the air and other gases finding their way into the system in one way or another, must be moved to permit the free flow of live steam or vapor to the radiators to preserve a uniform amount of heat, or an adaptation of heat to varying conditions. My invention has solved the problem, in that at the proper time, as varying conditions of the gases and liquids in the system require, each of the pumps is operated alternately with the other, and the load of the non-operative pump, during the period of its pumping idleness, is removed from the driving mechanism. I do not stop the movement of either pump remaining connected to and continuously operated by the driving mechanism during the period of its pumping activity.

I prefer to use, in a steam heating system, pumps of a rotary type, the air pump being of the type that uses liquid for passing the air and vapors through, and in both pumps I render them temporarily inoperative although continuously in rotation during a pumping period, by admitting air into the chamber of the pump in such a way that the

liquid therein is so removed from the pumping chambers that no pumping is being done during the time the air is in possession of the chambers; or by admitting air freely to gas pump, and stopping the flow of liquid to water pump suction.

The apparatus is so contrived, conditioned and automatically controlled that when no pumping at all is required, the pumping mechanism itself is stopped, and rests until conditions in the system require new pumping to be done, when the power will be again started, and the conditions within the system will determine whether the liquid pump or the air pump will first begin to pump; but whichever pump first begins to do pumping work, the other pump will remain functionally idle until the first pump is temporarily through with its work. Then it ceases to function, and the idle pump may begin its work.

Therefore, while some power is required to keep the two pumps constantly in motion during a pumping period, the pumping load itself is in each case interrupted, and the load on the power consists of the mere power required to move the idle pump and the active pump for rotative purposes only, plus the power required to cause the active pump to function in its work. The result is that there is a very marked saving in the power required to operate the system, and a considerable reduction in cost of manufacture. My method of controlling the pumps is believed to be an innovation in the art of pumping.

The apparatus of my invention is so related that the water pump is supplied directly from the return line of the system, while the air pump communicates with a receiving tank or reservoir in communication with the return line, so that the need for employing a receiver or reservoir which affords a common source of supply for the two pumps is avoided, and the apparatus accordingly simplified and rendered more efficient.

Further objects and details of the invention will appear from the description thereof, in conjunction with the accompanying drawings, wherein,—

50 Figure 1 is a diagrammatic view of the apparatus of the present invention as applied to a return line of a vacuum steam heating system;

55 Fig. 2 is a view partly in section showing the air pump and associated appliances;

Fig. 3 is an enlarged sectional view taken through line 3—3 of Fig. 2, looking in the direction of the arrows;

60 Fig. 4 is a top or plan view of the boiler check valve and associated air inlet valve for supplying atmospheric air to disable the air pump while the water pump is returning water to the boiler;

65 Fig. 5 is a vertical sectional elevation of the same;

Fig. 6 is an alternate form of device for admitting atmospheric air to disable the operation of the air pump; and

Fig. 7 is an enlarged detail of an air inlet valve for admitting air to the water pump to disable its action under the influence of vacuum in the system created by the operation of the air pump.

Referring to Figure 1, the principal units comprised in the apparatus of the present invention as applied to a steam heating system are the following: a motor A; an air pump B; a water pump C; a boiler D; a system of radiators E; and a vacuum tank F.

The boiler supplies steam, ordinarily under low pressure, to the radiator system through a steam line 10 leading upwardly from the boiler, and water of condensation is removed, and vacuum conditions created and maintained through a return line 11 which, as shown, leads directly to the water inlet side 12 of the centrifugal water pump C. The water admitted from the return line is driven through the pump and discharged back into the boiler through a boiler return line 13.

Vacuum is created within the return line 11, and thence throughout the system through a vacuum pipe 14 leading from the return line 11 to the vacuum tank F, which tank is provided with a suction line 15 leading from the vacuum tank through suitable couplings 16 to the air pump B.

In order to admit atmospheric air into the vacuum line during the period of time while water is being pumped through the boiler return line 13, a boiler check valve mechanism G is fitted into the boiler return line at a suitable point, which during the passage of water through the boiler return line is actuated in such a way as to admit atmospheric air through an air inlet valve mechanism H into the couplings 16, so that during this interval the effective operation of the air pump B will be suspended, and the pump will merely rotate idle without being subjected to a pumping load.

For a like purpose, in order to disable the operation of the water pump, while vacuum is being maintained in the suction line 15, an air inlet valve appliance I is provided, which is actuated through the conditions temporarily established in a connecting pipe 17, the parts being so related that during the interval of vacuum in the suction pipe line 15—16, atmospheric air will be admitted through a pipe 18 to the interior of the water pump, so that the operation of the pump will be disabled and suspended, though rotating idly while the motor A is energized.

When conditions within the system are such that no operation of either pump is necessary, the motor circuit will be broken through the automatic action of a switch J actuated by a diaphragm K, the interior of

which communicates with the vacuum tank F through the medium of a pipe 19 (see Fig. 1). A shutting off of the motor will occur after the system has been freed from water of condensation and a predetermined degree of vacuum has been established in the return line, as for instance eight inches, which degree of vacuum is adequate to collapse the diaphragm against the tension of a spring j,

10 and thereby actuate the switch J through the pull of a draw rod 20. It is not deemed necessary to describe in detail the construction of the switch, since any suitable type of switch may be employed for the purpose of controlling the flow of electrical energy through the motor circuit. The motor will thus remain idle until the vacuum has been reduced to a predetermined degree which will reverse the operation of the switch and 15 close the circuit, thus again actuating the motor. The fall in vacuum should be sufficient, however, to temporarily establish relatively low vacuum conditions to assist the water pump when its operation is resumed 20 in effectively discharging water accumulated in the system.

The construction of the various appliances heretofore referred to in general terms will now be described more in detail.

30 The air pump B comprises a rotor 21 having curvilinearly configured blades 22 which extend outwardly from a hub portion 23. The blades are connected through their centers by a circumferentially extending ring-shaped web 24 which terminates exteriorly of the hub to furnish, between the base of each blade, a cross passage or opening 25.

The rotor is mounted within an inner drum shaped chamber having a peripheral wall 26 and side walls 27 and 28 respectively. The peripheral wall, in its upper portion, merges into an air inlet conduit 29 which opens into the space immediately outside of the rotor blades, which rotate in a clockwise direction, 45 as indicated by the arrow in Fig. 2.

The peripheral wall, at a point immediately behind the air inlet conduit, is thickened to afford a block-off section 30 which is located at a point in proximate relation to air 50 outlet ports 33 cut through the side walls 27 and 28 of the inner drum-shaped chamber at a point substantially adjacent to the base of the blades. The inner wall of the block-off section lies in contiguous relation to the rotor blades, and this relationship continues up to the port of the inlet conduit, which is so formed as to direct the air inwardly in tangential relation to the tops of the blades 55 and into the enlarged annular space inside of the inner casing, which space continues in undiminished width up to a point adjacent the outlet port 33.

The outlet port opens into an outer side chamber 34, which is duplicated in the side chamber 35 on the opposite side, the side

chambers 34 and 35 being closed by the side walls 36 on the outer casing, which, as shown, is of boxlike formation and completely surrounds and encloses the inner rotor chamber. The side chambers 34 and 35 merge into one another and constitute portions of an outer air discharge chamber which discharges air through a pipe 37 preferably leading to the atmosphere.

70 The discharge of air through the pipe 37 is controlled by a diaphragm valve device L, the interior of which is connected with the vacuum return line 16 by a pipe connection 16^a, so arranged that when vacuum conditions are established, the diaphragm valve L will be lifted from its seat to allow the free discharge of air to the atmosphere through the pipe 37; but when atmospheric air is admitted into the vacuum line 16, the diaphragm valve L will close to impede but not entirely prevent the passage of air, so that under closed conditions there will be a seepage of air into the outer chamber of the rotor.

75 The peripheral wall 26 of the rotor chamber is provided with a port 38 through which the charge of water which is employed to effect the pumping of the air is expelled from the rotor chamber when the port 38 is open. This port is controlled by a valve 39 connected with a diaphragm 40 in communication with the suction pipe line 15—16 constituting a part of the vacuum line. This arrangement is such that when the diaphragm is subjected to the suction within the vacuum line, the valve 39 will be held closed and the water retained within the rotor chamber above the level of the axis of the rotor, but when the vacuum is broken by the admission of atmospheric air, the water within the rotor chamber will be expelled into the outer chamber, and the rotor will then cease to function as an air pump.

80 In order to stabilize the maintenance of a proper water level within the pump B, a reserve reservoir 41 is provided, which connects with the base of the pump casing by means of a pipe 42. Within the reservoir 41 is a post 43 which pivots a lever 44 carrying a float 45 at one end and a weight 46 at the other end.

85 The lever 44 has pivoted thereto a valve 47 which seats against the upper end of a drain pipe 48, the arrangement being such that after the water has risen in the reserve reservoir to the desired height, the valve 47 will be lifted and the excess water discharged through the drain pipe 48, back into the system.

90 In addition to the water discharge port 38, the rotor chamber is provided in its wall 122 with one or more relief vent ports 49 leading from the interior of the rotor chamber to the outer chamber, so that any excess of water coming into the rotor chamber may be expelled during the closed period of the valve 123.

39. A certain amount of water of condensation entrained with the air drawn into the pump will find its way into the interior of the rotor chamber, and this, together with the water seeping in from the outer chamber, will afford sufficient water within the chamber to maintain the air pumping operation during the closed period of the valve 39.

In operation, the rotation of the rotor or impeller will, while the valve 39 is closed, cause the water within the chamber to travel outwardly by centrifugal action and will fill the space within the peripheral wall, leaving the base of each of the pockets between the adjacent blades free from water until the blades reach the block-off section 30 of the chamber wall, which forces the water inwardly and expels the charge of air through the port 33 in the chamber wall. Air drawn in through the air inlet conduit 29 will meet the revolving ring of water at a point where it is suddenly released from the confinement of the block-off section 30, and in a more or less agitated condition, so that the air will readily find its way inwardly through the water ring, and thus each of the pockets will be charged with air, which will be carried around and forced out when the pocket reaches the block-off section. This forces the air out into the outer chamber and thence through the eduction pipe 37, and serves to develop vacuum conditions within the system, and the pumping action will continue until the valve 39 opens through the admission of atmospheric air, which breaks the vacuum and permits expansion of the collapsible diaphragm 40.

The side walls 27 and 28 of the rotor chamber, at their centers, are apertured to provide for the passage of the shaft upon which the rotor is mounted, and it will be noted that these apertures afford a sufficient clearance for the ingress of water to enter the rotor chamber, irrespective of the position of the valve 39. There is also a clearance between the rotor blades and the side walls of the chamber, so that the water entering at the center will be diverted outwardly and constitute what may be termed a water packing.

Moreover, the float in the reserve reservoir 41 is located at a sufficiently high level to rise only when an excessive amount of water is present, so that under no condition will the volume of water be sufficiently depleted to prevent the resumption of operations when pumping conditions are re-established within the air pump. Means other than a float controlled reserve reservoir might be provided for regulating the water volume in such a way as to always conserve a sufficient volume of water for operating purposes.

The expulsion of the water from the rotor casing into the reserve reservoir is due in part to the building up of a pressure within the outer chamber of the rotor as soon as

atmospheric air, admitted to the vacuum line 16, causes a closing of the diaphragm valve L and a consequent restriction of the air discharge. In these conditions, the pressure will be built up to the degree required to disable the pumping operation of the air pump, so that as long as such conditions are maintained the rotor will operate idly and without being subjected to a pumping load.

As soon, however, as atmospheric air is excluded from the vacuum line, pumping conditions will be very quickly re-established within the air pump. This appears to be due to the fact that as soon as free admission of atmospheric air through the air inlet H is completely closed, the escape of even a small volume of atmospheric air through the diaphragm valve L will reduce the pressure within the rotor casing and allow sufficient water to return to initiate the air pumping action of the rotor, which thereafter very quickly builds up a sufficient vacuum to fully open the diaphragm valve L, and also to close the valve 39, which completely restores the pump to its full effectiveness. It is therefore important to so relate the various portions of the apparatus in such a way that when the air discharged through the pipe 37 is impeded, a sufficient air pressure will be developed to lower the water level sufficiently to relieve the rotor from the air pumping load during the interval while atmospheric air is being freely admitted into the vacuum return line, and at the same time to make adequate provision for the inflow of air into the rotor casing to destroy the pressure and permit the return of water as soon as atmospheric air is excluded from the vacuum return line. The mechanism shown makes adequate provision for maintenance of the required equilibrium, although other means might be provided for attaining a similar result.

Means for operating the valve 39 to permit escape of water from the rotor chamber will now be described. These means are the check valve G in the boiler return line 13 operative to control the action of the air inlet valve H.

Referring to Fig. 5, the boiler check valve G comprises a shell 50 which is coupled into the boiler return line 13, which shell is provided on its interior with a stepped cross wall 51 affording a water discharge port 52 beveled on its upper face to afford a valve seat 53 which coacts with a tapered valve 54 carried by an open neck 55 through the base of which extends a stud 56 constituting the upper end of a valve stem 57.

Below the stud is located a tapered collar 58 which seats upon a flared or beveled rim 59 at the upper end of a bore 60 in a threaded nipple 61. A coil spring 62 is interposed between the tapered valve head 54 and a collar 63 mounted upon the stud 56. The cross pin 64 entered through the stud affords a connection between the stud and the base of the

open neck 55, so that, as the valve head 54 is lifted by the current of water flowing through the boiler return line, the valve stem 57 will be lifted, the parts, however, being so proportioned as to allow a slight amount of lost motion or freedom of action between the stem and the neck of the valve head.

The stem at its lower end carries a tapered air valve 65 which is provided with an open neck 66 through which is entered the reduced lower end 67 of the stem, a coil spring 68 being interposed between the base of the neck and a washer 69 carried by the stem.

Above the neck of the air valve is located a tapered valve collar 70, held in place by a flanged cross bar 71 carrying weights 71^a and held in place by a jamb nut 72. The valve collar 70 bears against a flared or tapered rim 73 at the lower end of the bore 60.

The air valve 65 seats against a tapered valve seat 74 at the upper end of a passage 75 formed in a nipple 76 which connects with a coupling 77 forming a part of the connections or couplings 16 leading to the dia-

phragm 40.

The operation of the features just described is as follows: While the water is being pumped through the boiler return line, the water check valve 54 will be lifted, and the lifting of this valve will unseat the air valve 65, allowing atmospheric air to flow through the pipe connections 16 to the collapsible dia-

phragm 40, which expands the same and unseats the valve 39, allowing the water in the rotor chamber to be expelled, so that the water ring will be broken and the rotor disabled and cease to act as an air pump, this disabling being assisted by the opening 49, a check valve 70^a in the pipe 15 preventing ingress of air upwardly into the vacuum tank F.

With the cessation of the water flow through the boiler return line, due to the exhaustion of the water of condensation in the return line of the radiator system, the valve 54 will seat itself and thus will allow the stem 57 to drop, thereby causing the air valve also to seat, closing the line of communication with the atmosphere. This will result in the establishment of a closed vacuum line through the radiator system, with the result that the valve 39 will be closed by the building up of a vacuum in the pipe connections 16, which connect with the vacuum line 15 leading to the vacuum tank and thence to the return line of the radiator system.

The springs 62 and 68 coact in such a way that when either the boiler check valve 54 or the air valve 65 is seated, either of these springs will hold the stem 57 down and keep the tapered collar 58 to its seat, thereby preventing the ingress of air to the system.

The provision of the valve 70 at the lower end of the nipple 61 is desirable in order to seal the bore through the nipple when the

water check valve 54 is open to permit the passage of water, since the absence of a seal at this point might permit the dripping of water from the boiler return line and its admission into the air inlet.

70

In lieu of the boiler check in the form shown in Fig. 5, a like result may be obtained by the use of the mechanism shown in Fig. 6, in which a flap valve 78 is provided, which is carried by a rock shaft 79 entered through the wall of a casing 80 provided with a beveled shoulder 81, which constitutes a seat for the flap valve, which when closed will occupy the position shown in dotted lines. As shown, this valve is located in the radiator return line 11 leading to the water pump instead of in the boiler return line 13, although it might be located in the latter if desired.

75

The flap valve 79, at its end, carries a lever arm 82 provided with an extension 83 carrying an adjustable weight 84. A link 85 is pivoted to the arm 82 and carries an air valve 86, which when lowered rests upon a seat 87 formed in a fitting 88 provided at its upper end with a flared rim 89. The air valve has a stem 90 concentric with it, which is slidable through a bridge 91.

85

The fitting 88 communicates with the air connections 16 for admitting air to disable the operation of the air pump. So long as water is passing through the boiler return line 13, the air valve will be lifted and atmospheric air admitted to the connections 16.

95

Valves of various forms might be employed for the same purpose, and it is not the intention to limit the invention to the employment of a valve of any particular form, since the essence of the idea involved is that of controlling the admission of air through the action of the water flow to or from the water pump, either by the action of a valve of suitable form or of some other instrumentality responsive to differential in pressures in the water return line. In this way, so long as a substantial volume of water is passing through the water return line, either to or from the water pump, atmospheric air will be admitted to disable the operation of the air pump, but as soon as the water flow ceases, the vacuum line will be sealed, so that water will return to the rotor chamber and again establish pumping conditions to the air pump.

100

In order to disable the action of the water pump, the mechanism shown in Fig. 7 is provided. This mechanism is designed to admit atmospheric air to the water pump so long as the vacuum creating system is closed and a vacuum maintained therein. This result is accomplished by the provision of an air valve 92 mounted on a stem 93 and backed by a spring 94 located within a tubular shell 95.

105

When the stem is thrust upwardly and

130

the valve lifted, air will be admitted through the valve into the pipe 18 leading to the water inlet 12 in the water pump C.

The tubular valve shell 95 is mounted 5 within a cross head 97 which carries a bellows formed diaphragm 98 carrying a cross bar 99 at its lower end. On the opposite side of the cross head a post 100 is provided to limit the upward movement of the cross bar 99. The pipe 17 communicates with the interior of the bellows formed diaphragm 98, which in turn connects with the vacuum line, as shown in Figure 1. With this arrangement, as long as conditions of vacuum are 15 maintained through the pipe 17, the diaphragm will be partially collapsed and lifted, thereby exerting an upward thrust on the air valve stem 93, which opens the air valve for the admission of air to the intake 20 of the water pump, which disables the action of the latter and prevents the pumping of water during the maintenance of vacuum conditions.

If desired, a thermostatically controlled 25 valve 101, of any suitable type, may be interposed in the vacuum line, preferably in the pipe 14 leading to the vacuum tank, which will respond to changes in temperature and close the vacuum line after the temperature has risen to a predetermined degree.

Operation

The operation of the apparatus will in the 35 main be understood from the foregoing description, but may be briefly summarized as follows: With the motor in operation and driving a line shaft connected with both of the pumps, the accumulated water in the 40 return line of the radiator system will be pumped through the water pump and through the return line to the boiler. The flow of water through the water system will open the vacuum line and admit atmospheric 45 air to the air pump, thereby disabling the operation of the latter, so that it will rotate idly so long as the water is passing either to or from the water pump. With the cessation of the water flow, the air valve will be 50 closed, and the closing of the air valve will establish conditions of effective operation in the air pump, so that air will be drawn from the vacuum tank and thence through the radiator return line, establishing and maintaining 55 vacuum conditions in the system and serving to induce the flow of low pressure steam through the radiators.

As the steam follows through the system, it will increase the temperature up to the 60 degree required to operate the thermostatically controlled valve 101, which will temporarily close communication with the vacuum tank. This will cause a rapid depletion of the air in the vacuum tank, and when the 65 vacuum has reached a predetermined point,

as for instance eight inches, will operate the diaphragm K to break the motor circuit and stop the motor. A like result will follow, even though the thermostatic valve remains open, provided the vacuum in the system reaches the degree required to operate the switch J which controls the motor circuit. During the operation of the air pump, the water pump will be disabled by the admission of atmospheric air through the control device I, so that, during these conditions, the water pump will work idly and without imposing any appreciable load upon the motor.

The mechanism as a whole is of simple construction, but by the provision of the controls described, combined together in harmonized relation to one another, the varying conditions in the system will be provided for, and the system will automatically adjust itself to meet such varying conditions.

I claim:

1. In an apparatus of the class described, the combination of an air pump, a water pump, and means for alternately effectively intermittently actuating the respective pumps, a water line within which the water pump is interposed, an air return line leading to the air pump, and means located in the water line and operable by the passage of water pumped therethrough during the normal operation of the water pump to open communication between the air return line and the atmosphere to admit atmospheric air to disable the operation of the air pump during the whole pumping period of the liquid pump.

2. In an apparatus of the class described, the combination of an air pump, a water pump, and means for actuating the pumps, a water line within which the water pump is interposed, an air return line leading to the air pump, means located in the water line and operable by the passage of water therethrough to open communication between the air return line and the atmosphere to admit atmospheric air to disable the operation of the air pump, and means communicating with the air return line and operable by the maintenance of vacuum conditions therein to admit atmospheric air to the water pump to disable the operation of the water pump.

3. In an apparatus of the class described, the combination of an air pump, a water pump, a motor, and a line shaft common to the two pumps for imparting pumping movements to the pumps, a water line within which the water pump is interposed, an air return line leading to the air pump, and means located in the water line and operable by the passage of pumped water therethrough during the normal operation of the water pump to open communication between the air return line and the atmosphere to admit atmospheric air to disable the effective

operation of the air pump during the whole pumping period of the liquid pump.

4. In an apparatus of the class described, the combination of an air pump, a water pump, a motor, a line shaft common to the two pumps for operating the pumps, a water line within which the water pump is interposed, an air return line leading to the air pump, means located in the water line and operable by the passage of water therethrough to open communication between the air return line and the atmosphere to admit atmospheric air to disable the operation of the air pump, and means communicating with the air return line and operable by the maintenance of vacuum conditions therein to admit atmospheric air to the water pump to disable the operation of the water pump.
5. In mechanism of the class described, the combination of a rotary water pump and a rotary air pump, a shaft upon which both of said pumps are mounted to rotate in unison, a motor for actuating said shaft, the air pump being provided with a rotor having blades adapted to coact with a body of water maintained in contact with said blades to effect the pumping of air, and the pump being provided with a valve and controlling means so related that when the valve is opened the body of water will be permitted to discharge from the rotor blades to disable the action of the pump, a water line within which the water pump is interposed, and means interposed in the water line and adapted during the passage of water therethrough to admit atmospheric air to actuate the valve controlling means to open the air pump valve and permit the discharge of water from contact with the rotor blades to disable the action of the air pump in pumping air.

6. In mechanism of the class described, the combination of a rotary water pump and a rotary air pump, a shaft upon which both of said pumps are mounted to rotate in unison, a motor for actuating said shaft, the air pump being provided with a rotor having blades adapted to coact with a body of water maintained in contact with said blades to effect the pumping of air, and the pump being provided with a valve and controlling means so related that when the valve is opened the body of water will be permitted to discharge from the rotor blades to disable the action of the pump, a vacuum line communicating with the air pump, a water line within which the water pump is interposed, and means interposed in the water line and adapted during the passage of water therethrough to admit atmospheric air to actuate the valve controlling means to open the air pump valve and permit the discharge of water from contact with the rotor blades to disable the action of the air pump in pumping air, a controlling device for the water pump in communication with the vacuum line leading to the air pump and

adapted upon the establishment of predetermined vacuum conditions therein to admit atmospheric air to the water pump to disable its action.

7. In mechanism of the class described, the combination of a rotary water pump and a rotary air pump, a shaft upon which both of said pumps are mounted to rotate in unison, a motor for actuating said shaft, the air pump being provided with a rotor having blades adapted to coact with a body of water maintained in contact with said blades to effect the pumping of air, and the pump being provided with a valve and controlling means so related that when the valve is opened the body of water will be permitted to discharge from the rotor blades to disable the action of the pump, a vacuum line communicating with the air pump, a water line within which the water pump is interposed, and means interposed in the water line and adapted during the passage of water therethrough to admit atmospheric air to actuate the valve controlling means to open the air pump valve and permit the discharge of water from contact with the rotor blades to disable the action of the air pump in pumping air, a controlling device for the water pump in communication with the vacuum line leading to the air pump and adapted upon the establishment of predetermined vacuum conditions therein to admit atmospheric air to the water pump to disable its action.
8. In mechanism of the class described, the combination of a rotary water pump and a rotary air pump, a shaft upon which both of said pumps are mounted to rotate in unison, a motor for actuating said shaft, the air pump being provided with a rotor having blades adapted to coact with a body of water maintained in contact with said blades to effect the pumping of air, and the pump being provided with a valve and controlling means so related that when the valve is opened the body of water will be permitted to discharge from the rotor blades to disable the action of the pump, a water line within which the water pump is interposed, and means interposed in the water line and adapted during the passage of water therethrough to admit atmospheric air to actuate the valve controlling means to open the air pump valve and permit the discharge of water from contact with the rotor blades to disable the action of the air pump in pumping air, a controlling device for the water pump in communication with the vacuum line leading to the air pump and adapted upon the establishment of predetermined vacuum conditions therein to admit atmospheric air to the water pump to disable its action.

9. In mechanism of the class described, the combination of a rotary water pump and a rotary air pump, a shaft upon which both of said pumps are mounted to rotate in unison, a motor for actuating said shaft, the air pump being provided with a rotor having blades adapted to coact with a body of water maintained in contact with said blades to effect the pumping of air, and the pump being provided with a valve and controlling means so related that when the valve is opened the body of water will be permitted to discharge from the rotor blades to disable the action of the pump, a vacuum line communicating with the air pump, a water line within which the water pump is interposed, and means interposed in the water line and adapted during the passage of water therethrough to admit atmospheric air to actuate the valve controlling means to open the air pump valve and permit the discharge of water from contact with the rotor blades to disable the action of the air pump in pumping air, a controlling device for the water pump in communication with the vacuum line leading to the air pump and adapted upon the establishment of predetermined vacuum conditions therein to admit atmospheric air to the water pump to disable its action.
10. In mechanism of the class described, the combination of a rotary water pump and a rotary air pump, a shaft upon which both of said pumps are mounted to rotate in unison, a motor for actuating said shaft, the air pump being provided with a rotor having blades adapted to coact with a body of water maintained in contact with said blades to effect the pumping of air, and the pump being provided with a valve and controlling means so related that when the valve is opened the body of water will be permitted to discharge from the rotor blades to disable the action of the pump, a water line within which the water pump is interposed, and means interposed in the water line and adapted during the passage of water therethrough to admit atmospheric air to actuate the valve controlling means to open the air pump valve and permit the discharge of water from contact with the rotor blades to disable the action of the air pump in pumping air, a controlling device for the water pump in communication with the vacuum line leading to the air pump and adapted upon the establishment of predetermined vacuum conditions therein to admit atmospheric air to the water pump to disable its action.

tions therein to admit atmospheric air to the water pump to disable its action, a motor circuit, a switch for controlling the motor circuit, means in communication with the vacuum line for actuating the switch upon the establishment of predetermined vacuum conditions therein to break the circuit and stop the motor, and a thermostatically controlled member in the vacuum line, adapted to be actuated by rise in temperature to a predetermined point to close the vacuum line and effect the establishment of the predetermined vacuum conditions aforesaid.

9. In mechanism of the class described, the combination of a water pump and a rotary air pump, the air pump being provided with a rotor having blades adapted to coact with a body of water maintained in contact with said blades to effect the pumping of air, and the pump being provided with an outlet from the space adjacent the rotor, affording a discharge for the water coacting with the rotor blades to disable the action of the pump, a vacuum line communicating with the rotor, a passage leading from the air pump for discharging air therefrom, valve means within said passage responsive to conditions within the vacuum line, a water line within which the water pump is interposed, means located in the water line and adapted during the passage of water therethrough to admit atmospheric air to the vacuum line, the parts being so related that during the admission of atmospheric air the discharge of air from the air pump will be restricted by partial closing of the valve means therein, and pressure conditions established within the pump adequate to reduce the water level to a point below effective pumping conditions, and the parts being further so related that when the inflow of atmospheric air is prevented the pressure within the air pump will be reduced to permit the return of water and thereby to re-establish air pumping conditions.

45 10. In mechanism of the class described, the combination of a rotary water pump and a rotary air pump, a shaft upon which both of said pumps are mounted to rotate in unison, a motor for actuating said shaft, the air pump being provided with a rotor having blades adapted to coact with a body of water maintained in contact with said blades to effect the pumping of air, and the pump being provided with an outlet from the space adjacent the rotor, affording a discharge for the water coacting with the rotor blades to disable the action of the pump, a vacuum line communicating with the rotor, a passage leading from the air pump for discharging air therefrom, valve means within said passage responsive to conditions within the vacuum line, a water line within which the water pump is interposed, means located in the water line and adapted during the passage of water therethrough to admit atmospheric air

to the vacuum line, the parts being so related that during the admission of atmospheric air the discharge of air from the air pump will be restricted by partial closing of the valve means therein, and pressure conditions established within the pump adequate to reduce the water level to a point below effective pumping conditions, and the parts being further so related that when the inflow of atmospheric air is prevented the pressure within the air pump will be reduced to permit the return of water and thereby to re-establish air pumping conditions.

11. In an apparatus of the class described, the combination of an air pump, a water pump, and means for alternately effectively intermittently actuating the respective pumps, a water line within which the water pump is interposed, an air line leading to the air pump, and means located in the water line and operable by the passage of water pumped therethrough during the normal operation of the water pump to disable the operation of the air pump during the whole pumping period of the liquid pump.

12. In an apparatus of the class described, the combination of an air pump, a water pump, and means for actuating the pumps, a water line within which the water pump is interposed, an air line leading to the air pump, means located in the water line and operable by the passage of water therethrough to disable the operation of the air pump, and means communicating with the air return line and operable by the maintenance of vacuum conditions therein to disable the operation of the water pump.

13. In an apparatus of the class described, the combination of an air pump, a water pump, a motor, and a shaft common to the two pumps for imparting pumping movements to the respective pumps, a water line within which the water pump is interposed, an air line leading to the air pump, and means located in the water line and operable by the passage of pumped water therethrough during the normal operation of the water pump to disable the operation of the air pump during the whole pumping period of the liquid pump.

14. In an apparatus of the class described, the combination of an air pump, a water pump, a motor, and a shaft common to the two pumps for operating the pumps, a water line within which the water pump is interposed, an air line leading to the air pump, means located in the water line and operable by the passage of water therethrough to open communication between the air line and the atmosphere to admit atmospheric air to disable the operation of the air pump, and means communicating with the air line and operable by the maintenance of vacuum conditions therein to disable the operation of the water pump.

15. In an apparatus of the class described, the combination of liquid and gas pumps, and means for operating the pumps, a liquid line within which the liquid pump is interposed, 70
 5 a gas line leading to the gas pump, means responsive to the flow of water in the liquid line for preventing the effective operation of the gas pump, when water in predetermined volume flows to the water pump, and means
 10 responsive to vacuum conditions and adapted, when suction in predetermined amount is developed in the gas line by the effective operation of the gas pump, to disable the effective operation of the liquid pump. 75
 15 16. In an apparatus of the class described, the combination of liquid and gas pumps, and means for constantly rotating the two pumps in unison, a liquid line within which the liquid pump is interposed, a gas line leading to 80
 20 the gas pump, means responsive to the flow of water in the liquid line for preventing the effective operation of the gas pump, when water in predetermined volume flows to the water pump, and means responsive to vacuum conditions in the gas line for causing an intermittent operation of the pump operating means to the end that periodic low vacuum conditions may obtain during the period of effective operation of the liquid pump. 85
 25 conditions and adapted, when suction in predetermined amount is developed in the gas line by the effective operation of the gas pump, to disable the effective operation of the liquid pump. 90
 30 17. In an apparatus of the class described, the combination of liquid and gas pumps, and means for operating the pumps, a liquid line within which the liquid pump is interposed, a gas line leading to the gas pump, means 95
 35 responsive to the flow of water in the liquid line for preventing the effective operation of the gas pump, when water in predetermined volume flows to the water pump, and means responsive to vacuum conditions and adapted, when suction in predetermined amount is developed in the gas line by the effective operation of the gas pump, to disable the effective operation of the liquid pump, and means responsive to vacuum conditions in the gas line for causing 100
 40 an intermittent operation of the pump operating means to the end that periodic low vacuum conditions may obtain during the period of effective operation of the liquid pump. 105
 45 18. In an apparatus of the class described, the combination of liquid and gas pumps, and means for constantly rotating the two pumps in unison, a liquid line within which the liquid pump is interposed, a gas line leading to the gas pump, means responsive to the flow of water in the liquid line for preventing the 110
 50 effective operation of the gas pump, when water in predetermined volume flows to the water pump, and means responsive to vacuum conditions and adapted, when suction in predetermined amount is developed in the gas 115
 55 line and adapted upon predetermined rise of temperature of gas in the gas line to arrest the pumping of gas. 120
 60 19. In an apparatus of the class described, the combination of liquid and gas pumps, and means for operating the pumps, a liquid line within which the liquid pump is interposed, a gas line leading to the gas pump, means responsive to the flow of water in the liquid line for preventing the effective operation of the gas pump, when water in predetermined volume flows to the water pump, and means responsive to vacuum conditions and adapted, when suction in predetermined amount is developed in the gas line by the effective operation of the gas pump, to disable the effective operation of the liquid pump, and means responsive to vacuum conditions in the gas line for causing an intermittent operation of the pump operating means to the end that periodic low vacuum conditions may obtain during the period of effective operation of the liquid pump. 125
 65 20. In an apparatus of the class described, the combination of liquid and gas pumps, and means for constantly rotating the two pumps in unison, a liquid line within which the liquid pump is interposed, a gas line leading to the gas pump, means for preventing the effective operation of the gas pump, when water in predetermined volume flows to the water pump, and means responsive to vacuum conditions and adapted, when suction in predetermined amount is developed in the gas line by the effective operation of the gas pump, to disable the effective operation of the liquid pump, and means responsive to vacuum conditions in the gas line for causing an intermittent operation of the pump operating means to the end that periodic low vacuum conditions may obtain during the period of effective operation of the liquid pump. 130

um or air pump, thereby rendering it ineffective when the water pump functions, and vice versa to close such atmospheric inlet when the water pump ceases to function, so that the 5 vacuum or air pump may function effectively, means for operating the pumps, a thermostatically controlled valve in the air line, a switch for energizing and de-energizing the motor, and means responsive to vacuum conditions within the system for controlling the 10 switch and de-energizing the motor when a given degree of vacuum has been obtained.

22. In a pumping system of the class described, the combination of a liquid line, a 15 liquid pump suitably interposed in the liquid line to pump liquid therethrough during the period of an adequate supply of liquid, a gas line, a gas pump suitably connected to the gas line to pump gas therethrough, power 20 means for driving the pumps, and means responsive to the quantitative status of the liquid line, to maintain communication from the atmosphere to the gas pump during the period of an adequate supply of liquid 25 to the liquid pump and to close such communication when the liquid supply is inadequate, thereby providing separate periods for pumping liquid and gas through and from the respective lines.

30 23. In a pumping system of the class described, the combination of a liquid line, a liquid pump suitably interposed in the liquid line to pump liquid therethrough during the period of an adequate supply of liquid, a gas 35 line, a gas pump suitably connected to the gas line to pump gas therethrough, a thermostatic valve interposed in the gas line and adapted upon predetermined rise of temperature of gas to arrest the increase of vacuum 40 in the gas line, and means responsive to the quantitative status of the liquid line, to maintain communication from the atmosphere to the gas pump during the period of an adequate supply of liquid to the liquid pump and 45 to close such communication when the liquid supply is inadequate, thereby providing separate periods for pumping liquid and gas through and from the respective lines.

24. In a pumping system of the class described, the combination of a liquid line, a liquid pump suitably interposed in the liquid line to pump liquid therethrough during the period of an adequate supply of liquid, a gas line, a gas pump suitably connected to the 50 gas line to pump gas therethrough, power means for driving the pumps, means responsive to the quantitative status of the liquid line, to maintain communication from the atmosphere to the gas pump during the period 55 of an adequate supply of liquid to the liquid pump, and to close such communication when the liquid supply is inadequate, thereby providing separate periods for pumping liquid and gas through and from the respective 60 lines, and control means also responsive to 65

quantitative conditions in the liquid line for turning the power means on and off to provide for certain periods of inactivity to allow the vacuum to fall to a predetermined low point desirable for pumping liquid.

25. In a pumping system of the class described, the combination of a liquid line, a liquid pump suitably interposed in the liquid line to pump liquid therethrough during the period of an adequate supply of liquid, a gas line, a gas pump suitably connected to the gas line to pump gas therethrough, a thermostatic valve interposed in the gas line and adapted upon predetermined rise of temperature of gas to arrest the increase of vacuum in the gas line, power means for driving the pumps, means responsive to the quantitative status of the liquid line, to maintain communication from the atmosphere to the gas pump during the period of an adequate supply of liquid to the liquid pump, and to close such communication when the liquid supply is inadequate, thereby providing separate periods for pumping liquid and gas through and from the respective lines, and control means also responsive to quantitative conditions in the liquid line for turning the power means on and off to provide for certain periods of inactivity to allow the vacuum to fall to a predetermined low point desirable for pumping liquid.

In witness that I claim the foregoing I have hereunto subscribed my name this 8th day of May 1929.

LUCIAN F. EASTON.
